UNITED STATES PATENT OFFICE.

LOU BELLE ANDERSON, OF CELINA, TEXAS.

FUSE-BLOCK.

1,376,392.

Specification of Letters Patent.

Patented May 3, 1921.

Application filed January 19, 1920. Serial No. 352,519.

To all whom it may concern:

Be it known that I, LOU BELLE ANDERSON, a citizen of the United States, residing at Celina, in the county of Collin and State of Texas, have invented certain new and useful Improvements in Fuse-Blocks, of which the following is a specification.

This invention relates to improvements in fuse blocks.

10 The invention is in some respects an improvement on the fuse block covered by Letters Patent No. 1,113,528 issued to me, as administratrix, on October 13, 1914, but embodies several other features as will be 15 hereinafter pointed out.

15 The fuse block covered by said patent has certain objections, one of which is that a special fuse is required, and the other is that the lineman must reach up above the primary 20 circuit wires to remove and replace the fuses, thus bringing his body into near relation to said wires. Further the said device is 25 designed for one particular fuse and larger or smaller fuses could not be used unless specially made.

30 The object of this invention is to provide a fuse block whereby the fuses can be removed and replaced by the lineman without bringing his body into close proximity with the primary circuit wires.

35 A further object is to provide a fuse block so constructed that fuses of various sizes and amperage and of the cartridge type now in common use can be used therein, thus precluding the necessity of using an especially made fuse of a certain size.

40 In carrying out the invention I interpose a non-conducting fuse block in one side of a primary electric circuit, the wires of the said circuit entering the block from opposite sides near the top of the latter and terminating. Vertically disposed fuse receiving 45 apertures provided within the block receive the fuses, resilient sockets at the upper ends of the said apertures and connecting with the circuit wires receiving the upper terminals of the said fuses.

50 A non-conducting plug having a conducting plate along its upper face with resilient sockets secured thereto which receive and retain the lower terminals of the fuses is inserted into a recess in the lower part of the block and retained therein by a non-conducting pin. Thus, by inserting the 55 fuses into the sockets on the plug and then inserting the plug into the block the fuses

are replaced without touching them while they are in contact with the circuit. This may be done by the lineman from below the block, thereby enabling him to avoid the 60 dangers attendant upon coming into close proximity to the circuit wires.

By making the sockets on the plug of stiffer material than those within the block, those within the block would release first 65 upon the withdrawal of the plug and permit the fuses to be withdrawn with the plug. The resilient sockets contracting so as to hold smaller fuses and expanding to receive larger ones than those especially made for use with 70 my device, would permit of fuses of various sizes and amperages being used.

Upon the circuit becoming overcharged by lightning or otherwise one fuse would be blown out and any arc that might occur 75 within the aperture of the block would be destroyed by the blowing out of the other fuse, thus obviating the destruction of the block which would occur if a single fuse was employed. A non-conducting pin would retain the plug within the block against the expansion of the gases within the block caused by the blowing out of the fuses, the said gases escaping through passages communicating with the outer surface of the 85 block.

The invention will be more readily understood from a reading of the following specification and by reference to the accompanying drawings, in which an example of the 90 invention is shown, and wherein:

Figure 1 is a view in elevation of a device embodying the invention, showing a portion of the bracket upon which the same is mounted,

95 Fig. 2 is a plan view showing the cap broken away from one side of the block,

Fig. 3 is a sectional view of the block with the plug shown partly in section and partly in elevation,

100 Fig. 4 is a view taken on the line 4-4 of Fig. 1,

Fig. 5 is a side view of the device partly in elevation and partly in section,

Fig. 6 is an elevation of the plug with the 105 fuses inserted in the sockets, and

Fig. 7 is a detail of one of the sockets within the block.

In the drawings the numeral 10 designates the body of a fuse block preferably formed 110 of porcelain, having a rectangular projection 11 extending longitudinally along the

back of the body and integral with the latter. This projection contacts the support 12 upon which the body is mounted and acts to maintain the body at a substantial distance from the said support, to which the body is secured by means of bolts 13.

Within the body are vertically disposed tubular fuse receiving apertures 14 opening in the open bottom of the body and terminating in its upper portion, the said apertures being laterally enlarged at their ends. With the top of the aperture 14 there communicates an opening 15 of smaller diameter than the said aperture and opening at the 15 top of the body.

Binding posts 16 engage within the openings 15, each post having transversely extending annular flanges 17 at their lower ends. These flanges engage on annular shoulders 18 at the tops of the apertures 14, the said flanges being surrounded by a seal 19 of wax which is poured into the enlarged termination of the said apertures. Resilient sockets 20 are secured to the lower ends of 20 the binding posts and disposed to receive the upper terminals 20' of fuses 14' disposed within the apertures 14.

The wires 21 comprising one side of a primary electric circuit enter the body from 30 opposite sides of the latter through horizontal passages 22 communicating with the apertures 15, and are engaged in permanent contact with the binding posts 16 by means of binding screws 23.

35 A cap 24 having a depending apron extending around its edge surmounts the body. Thus the top of the body is made water proof and the apron tends to cause the water to drip free of the body and not run down 40 the sides of the latter.

A non-conducting plug 25, the lower portion of which assumes the shape of a handle is inserted into the lower end of the body which is open. The plug has a conducting 45 plate 26 secured along its upper face by means of lugs 27 having nuts disposed within transverse slots 28. Upwardly directed resilient sockets 29 integral with the plate 26 are disposed within the apertures 50 14. The said sockets receive the lower terminals 29' of the fuses 14'.

By inserting the lower terminal 29' of a fuse into each of the sockets 29 and then inserting the plug into the lower portion of 55 the body the upper terminals 20' of the fuses would be received within the sockets 20.

A horizontal passage 30 through the front 60 of the body near the bottom of the latter permits a non-conducting pin 31 to pass through the said passage and movably engage in a horizontally disposed opening 32 extending partly through the plug, thereby retaining the plug within the body. Thus, 65 the lineman can insert the fuses quickly and

easily without the aid of tools. Also, by grasping the handle shaped bottom of the plug and inserting the said plug into the bottom of the body from below the latter he can avoid the danger of electrocution 70 attendant upon bringing his body into close proximity to the primary circuit wires.

When a fuse blows out, the expanded gases caused thereby escape from the aperture 14 through a passage 33 leading from 75 the said aperture and opening on the outside of the body, the pin 31 obviating the displacement of the plug from the body by the said gases.

It is noted that the normal path of the 80 current is through one of the wires 21 leading into one side of the body, thence through the binding post 16 and socket 20 into the fuse. The fuse conveys that current to the socket 29 and thence the current passes 85 through the conducting plate 26 to the socket 29 at its opposite end and into another fuse. The latter fuse conveying the current to the socket 20 and through the binding post into the wire which passes out 90 of the block at the opposite side of the latter from the first named wire.

It is pointed out that when the circuit becomes overloaded or shortened for any reason the fuses blow out and break the circuit, 95 thereby precluding the damage to property commonly caused by overloaded or short circuited wiring, any arcing which might occur between the terminals of one fuse would be destroyed by the blowing out of the other 100 fuse and thereby obviating the damaging of the body caused by such arcing when a single fuse is employed, the web 34 between the apertures 14 precluding the possibility 105 of the current arcing across from one wire of the circuit to the other.

The resilient sockets contract to engage a smaller fuse and expand to receive a larger fuse than the one especially designed for use with this fuse block, thereby permitting the 110 standard cartridge type fuses of various sizes and amperages to be used. The sockets 29 being made of stiffer material than the sockets 20 would cause the latter to release the fuses when the pin 31 is removed from 115 the plug and the plug is withdrawn from the body; thus, the fuses would remain in the sockets 29 and be withdrawn from the apertures with the plug.

It will be seen that by the use of this device a number of the objectionable and dangerous features of the fuse blocks formerly used are substantially overcome and remedied.

What I claim, is:

1. In a fuse block an insulating body provided with a plurality of longitudinal apertures and having a main bore at its lower end which leads into the apertures, resilient sockets held within the upper ends of the 130

apertures, an insulating plug adapted for insertion within the main bore to close the same and to be removed therefrom, means to lock the insulating plug within the main bore, a conducting plate secured to the inner end of the insulating plug, resilient sockets connected with the conducting plate and being stiffer than the first named resilient sockets, fuses having their opposite ends held 10 within the two sets of sockets, and means for connecting wires with the first named sockets.

2. In a fuse block, an insulating body adapted to be arranged in an upright position and having a plurality of longitudinal apertures and having a main bore at its lower end leading into the apertures, said body being provided at its upper end with

openings leading into the apertures and having a smaller diameter, binding posts held 20 within said openings, a cap arranged upon the upper end of the body and covering said openings, resilient sockets carried by the binding posts and arranged within said apertures, an insulating plug adapted for 25 insertion within the main bore to close the same and to be removed therefrom, resilient sockets connected with the insulating plug and arranged within said apertures and being stiffer than the first named resilient 30 sockets, means electrically connecting the last named sockets, and fuses having their opposite sides inserted within the two sets of sockets.

In testimony whereof I affix my signature. 35
LOU BELLE ANDERSON.
